Application August 29, 1955, Serial No. 531,096

7 Claims. (Cl. 132—50)

This invention relates to clamps and comprises a new and improved clip, particularly suited for setting the hair and holding waves in place.

The primary object of my invention is to simplify the construction of hairpins and clips, and thus reduce the cost of manufacture of these items.

Another important object of my invention is to eliminate scrapping problems in the manufacture of clips and hairpins.

Each of the embodiments of my invention, described in the following detailed description, are formed from a single sheet of material. Initially, the clip or pin is stamped from the sheet and at the same time the dye forms a number of slits in the blank which define manipulating ears used to open the clip. After stamping, the blank is folded transversely across its center so that one-half of the stamping overlies the other half. Next, the ears defined by the slits are bent out of the plane of each half of the clip and extend outwardly and away from the ends of the stamping. The transverse fold serves as a hinge for each half of the clip and by squeezing the ears together the two halves of the clip separate about the fold. Normally each half of the clip lies in substantially parallel planes.

Each end of the stamping comprises one or more tines which serve as gripping members. Clips formed with single tines at each end may be used as hairpins, while double-tined clips are better suited for the setting of the hair. It will be apparent from the following detailed description, however, that my invention may be incorporated into many other forms of clamping devices. That is, although the illustrated embodiments are particularly suited for use in the hair-dressing art, they may be used in many diverse fields.

My invention will be better understood and appreciated from the following detailed description of a number of embodiments thereof, selected for purposes of illustration and shown in the accompanying drawing in which:

Figure 1 is a plan view of a sheet of material cut into hairpin and clip blanks,

Figure 2 is a plan view of a fully formed clip made from the clip blank shown in Figure 1;

Figure 3 is a cross-sectional view taken along the corresponding section line of Figure 2;

Figure 4 is a plan view of a blank of another embodiment of a pin constructed in accordance with my invention;

Figure 5 is a plan view of a fully formed pin made from the blank shown in Figure 4;

Figure 6 is a cross-sectional view taken along the corresponding sectional line of Figure 5;

Figure 7 is a plan view of still another embodiment of pin blank constructed in accordance with my invention;

Figure 8 is a cross-sectional view of a pin formed from the blank shown in Figure 7 and taken along the section line suggested in that figure;

Figure 9 is a plan view of still another embodiment of pin blank constructed in accordance with my invention,

2

Figure 10 is a cross-sectional view of a pin formed from the blank shown in the Figure 9, and

Figure 11 is a cross-sectional view of still another pin constructed in accordance with my invention.

5 The narrow strip of material 20 illustrated in Figure 1 has a number of lines on its surface which represent cuts in the stock. These cuts divide the stock into two complete and independent clamps 22 and 24. The cuts 26 and 28 in Figure 1 define the outline of the clip blank 10 22 while the cuts 28 and 30 define the outline of the pin 24.

The clip blank 22 defined by the cuts 26 and 28 is shown fully formed in Figure 2. Extending transversely across the center of the clip blank 22 are a pair of cuts 32 and 34 which extend inwardly from the sides of the stamping to a pair of coextensive longitudinal slits 36 and 38. As suggested in the introduction of this specification, the slits 32, 34, 36 and 38 may be introduced into the material during the initial stamping operation.

15 20 After the blank is formed, it is folded in half along the slits 32 and 34, and the portions of the blank defined by the slits are bent outwardly and away from the ends of the stamping as suggested in Figures 2 and 3. In this manner, manipulating ears 44, 46, 48 and 50 are formed 25 in the clip to facilitate opening.

As shown in Figure 2, the cut 26 defines a pair of tines 40 and 42 at one end of the blank which overlie similar tines 52 and 54 formed by the cut 28 at the opposite end of the blank. These tines normally lie in parallel planes 30 and may be spread about the fold which is contiguous with the slits 32 and 34 by squeezing the manipulating ears 44, 46, 48 and 50 together. Thus, it is seen that the fold serves as a hinge for the clip. Obviously, if the material used to form the blank is resilient, when the 35 manipulating ears are released, the tines 40 and 42 formed in one-half of the stamping will assume their normal position adjacent the tines 52 and 54 formed in the other half of the device.

The pin 24 shown in blank form in Figure 1 is formed 40 in a manner identical to that described for the clip 22. The pin 24 differs from the clip only in that it has but one tine on each end to serve as a gripping member.

The manner in which scrapping is eliminated is clearly 45 illustrated in Figure 1. The cut 28 which separates the clip 22 from the pin 24 forms double tines at one end of the clip 22 and a single tine at the adjacent end of the pin 24. This overlapping pattern utilizes all of the stock, thus no waste material results.

The pin blank shown in Figure 4 is very similar to the 50 pin blank 24. It too may be mass produced without a scrapping problem by alternatively stamping a pin and a clip. It will be noted that coextensive longitudinal slits 56 and 58 are cut in the central portion 60 of the blank and a transverse slit 62 coincident with a fold line

55 64 interconnects the centers of the longitudinal slits. The longitudinal and transverse slits 56, 58, and 62 define manipulating ears 66 and 68. After the blank is formed by cutting along lines 69 and 71, it is folded over along the line 64 and the ears 66 and 68 are bent out of the planes of the halves of the blank to the position illustrated in Figure 6. To separate the tines 70 and 72 defined by the cuts 69 and 71, the ears 66 and 68 are pressed together. When the ears are released, the tines 60 return to the closed or biased position.

65 Figures 7 and 8 illustrate still another embodiment of pin. The central portion 74 of the stamping illustrated in Figure 7 is folded along line 76 which extends transversely across its center. Adjacent the fold line 76 are two pairs of longitudinal slits 78 which are joined at their outer ends by transverse slits 80. The slits 78 and 80 in each half of the blank define ears 82 which are folded over and out of the planes of each of the halves of the

blank in the manner shown in Figure 8. The ears 82 extend outwardly and away from the ends of the clip so that pressure exerted on them will open the pin above the fold line 76.

The blank shown in Figure 9 contains the slits 78 just as the pin of the preceding embodiment. However, these slits are joined by transverse slits 84 at their inner ends rather than at their outer ends as in the preceding embodiment. The slits 78 and 84 define manipulating ears 86 which are bent out from the plane of the halves of the pin in a manner identical to the ears 66 and 68 described above. Once again, pressure exerted on these ears will spread the pin about the fold line 76.

It will be apparent from the foregoing description that each of the configurations of the manipulating ears may be used with either one or two or any number of tines as gripping members. Moreover, although the manipulating ears have been described in the environment of a hair clip or pin, they may be used in many other forms of clamping devices. For example, tweezers or tie pins may take the form of the clamps described above. In Figure 11, I have illustrated a clamping device very similar to that shown in Figure 3 but particularly designed to serve as an eyelash holder. A slight curvature has been introduced into the tines and they are somewhat elongated. Preferably such a device would be formed with single tines at each end.

From the foregoing description, those skilled in the art will appreciate that numerous modifications of my invention may be made without departing from the spirit thereof. Therefore, it is not my intention to limit the breadth of my invention to the specific embodiments illustrated and described, but rather its scope is to be determined by the appended claims and their equivalents.

Having now described my invention, I claim:

1. A clip adapted to be formed from a continuous length of thin resilient material comprising gripping members formed in each end of the material, a central portion of the material joining the inner ends of the gripping members, said central portion being folded across its center with one of the gripping members overlying and being parallel to the other of said gripping members, the fold in the central portion serving as hinge means for the gripping members, and manipulating members formed on each side of the fold in the central portion and extending outwardly at an angle to the planes of the gripping members whereby pressure exerted on the manipulating members causing said members to move towards each other separates the gripping members about the hinge means.

2. A clip comprising a sheet of thin resilient material folded over across its center into two parallel and closely adjacent portions, at least one tine formed in each portion of the sheet, and manipulating members formed in the portions on each side of the fold and extending away from the ends of the tines at an angle to the planes of the tines whereby pressure applied to the manipulating members causes the tines to spread about the fold in the sheet.

3. A clip comprising a sheet of thin resilient material folded over across its center dividing the sheet into two closely adjacent and parallel parts, an H shaped cut in the central portion of the material with the horizontal portion of the H shaped cut being coincident with the fold and forming a pair of manipulating members one in

each part, said manipulating members being bent outwardly from the top and bottom of the H shaped cut and away from the ends of the material at an angle to the planes of the parts, and gripping members formed in the end portions of the material.

4. A clip comprising a sheet of thin resilient material folded over across its center, a cut in the material covering a portion of the fold, a second cut in the material perpendicular to and meeting the first cut, said first and second cuts forming manipulating members for the clip, said manipulating members being bent slightly out from the plane of the material and extending away from the ends of the material when said material is folded, said members terminating short of the fold and gripping members formed in the end portions of the material and lying parallel and in immediate proximity to each other when the manipulating members are in their normal position.

5. A clip comprising a sheet of thin resilient material folded over across its center into two parallel and immediately adjacent portions, intersecting transverse and longitudinal cuts in the central portion of the material on each side of the fold, the portions of the material defined by the cuts being bent outwardly from the planes of the adjacent portions and extending away from the ends of the material when said material is folded across its center, and gripping members formed in the end portions of the material normally lying in parallel planes.

6. A clip formed from a single thin elongated sheet of resilient material, said sheet being folded transversely across its center causing one half of said sheet to overlie the other half of said sheet in parallel and immediately adjacent planes, a pair of spaced apart longitudinal cuts in each half of the material and adjacent the fold, a transverse cut in each half of the material and interconnecting the ends of the longitudinal slits adjacent the fold, the portions of the material defined by the transverse and longitudinal slits being displaced from the planes of the halves of the material and at an angle thereto with their ends terminating inwardly of the fold, whereby when the last named portions are pressed together, the halves of the material will separate about the fold.

7. A clip formed from a single sheet of thin elongated resilient material, said material being folded transversely across its center causing one half of said material to overlie the other half of the material, a pair of longitudinal spaced apart cuts in the central portion of the material crossing the fold, transverse cuts in the material extending outwardly from each of the longitudinal cuts, said cuts defining four manipulating ears at the fold in the material, said manipulating ears being bent outwardly at an angle to the halves of the sheet and away from the ends of the sheet, whereby pressure applied to the manipulating ears causes the halves of the material to spread about the fold in the central portion.
